UNITED STATES PATENT OFFICE.

BENJAMIN R. ROACH, OF VINTON, VIRGINIA.

TRAIN-STOP.

1,147,550.

Specification of Letters Patent. Patented July 20, 1915.

Application filed February 9, 1915. Serial No. 7,076.

To all whom it may concern:

Be it known that I, BENJAMIN R. ROACH, a citizen of the United States of America, residing at Vinton, in the county of Roanoke and State of Virginia, have invented new and useful Improvements in Train-Stops, of which the following is a specification.

This invention relates to improvements in 10 automatic train stops and has particular application to a train stopping device whereby the propelling power of the motor car may be cut off and the brakes applied in the event of the engineer disregarding a danger signal.

In carrying out the present invention, it 20 is my purpose to provide an automatic train stop by means of which the throttle valve lever will be unlocked and swung to closed position to cut off the flow of steam from the steam dome of the boiler to the drive cylinders of the engine, and the pressure in the 30 brake pipe reduced to effect an application of the brakes to the wheels.

It is also my purpose to improve and simplify the general construction of automatic 35 train stops; to provide a train stop which will operate efficiently and effectively under all conditions; and to produce a device of 40 the class described which may be installed and maintained at small cost.

With the above and other objects in view, the invention consists in the construction, combination and arrangement of parts hereinafter set forth in and falling within the 45 scope of the claims.

In the accompanying drawings: Figure 1 is a fragmentary side elevation of a trackway and locomotive thereon showing my invention installed. Fig. 2 is a cross sectional view through the trackway and locomotive thereon, part of the locomotive being broken away. Fig. 3 is a diagrammatic plan view showing the motor and throttle lever and 50 the connections between such motor and lever. Fig. 4 is a longitudinal sectional view through the motor and its support. Fig. 5 is a side elevation of the valve controlling device detached from the engine, the parts 55 being shown on an enlarged scale. Fig. 6 is a cross sectional view through the device. Fig. 7 is a sectional view through the controlling valve showing the plug in normal or inactive position. Fig. 8 is a similar 60 view through the valve showing the plug in active position.

Referring now to the drawings in detail, 1 designates a trackway and 2 a locomotive or other appropriate form of motor car that traverses the trackway. In accordance 60 with my present invention, obstacles 3 are arranged along the trackway at both sides thereof and spaced apart suitable distances and controlled from the respective signals or from other traffic controlling apparatus. 65 In the present instance, each obstacle 3 comprises a horizontal shaft 4 arranged longitudinally of the trackway upon one side of the particular line of rails thereof and journaled in alining bearings 5 carried by adjacent ties of the trackway. One end of the shaft 4 is connected through suitable mechanism 6 with the signal blade of the adjacent semaphore while the opposite end of such shaft is equipped with an arm 7 disposed at 70 right angles to the shaft and having the upper end thereof provided with a roller 8 rotatable about an axis at right angles to the track. When the signal blade goes to danger position the shaft 4 is revolved and 75 80 85 90 95 100 105 110 115 danger position the shaft 4 is revolved and 80 85 90 95 100 105 110 115

Depending from the locomotive 2 or other 85 motor car is a valve controlling device 9 comprising a horizontal base plate 10 secured to the frame of the motor car. Fastened to the under surface of the base plate 10 adjacent to the end edges of the latter are 90 the respective ends of a bowed spring 11 having the central portion thereof spaced apart from the under surface of the base plate and curved upwardly to form an eye 12, the top wall of the eye being formed 95 with a slot 13 registering with an opening 14 formed in the base plate 10. Passed through the slot 13 and the opening 14 is a vertical rod 15 having the lower end thereof disposed within the eye 12 and formed with 100 an eye 16 and through the eyes 12 and 16 is passed a pin 17 serving as a connection between the spring and the lower end of the rod 15. The upper end portion of the rod 15 is passed through an opening in a collar 105 18 and connected with the collar 18 at diametrically opposite points are the upper ends of standards 19 upstanding from the base plate 10, while projecting upwardly from one of the standards 19 and secured thereto is a bracket arm 20 having the upper end thereof bent at right angles to itself as

at 21 and formed with a series of openings 22 spaced apart. Pivoted to the right angular portion 21 of the bracket arm 20 is a lever 23 having one end thereof pivotally connected to the upper end of the rod 15 as at 24 and the opposite end connected through the medium of a link 25 with the handle 26 of a valve 27 located in the brake pipe of the air brake system of the train. In the present instance, the rod 15 is formed with ratchet teeth 28 and engaging the teeth 28 is a spring actuated dog 29 pivoted to one of the standards 19 and normally engaging the ratchet teeth under the action of its spring.

In practice, when the locomotive runs by a danger signal the under surface of the bowed spring 11 engages the roller 8 and rides over the latter with the effect to slide the rod 15 upwardly and in the upward movement of the rod 15 the lever 23 is swung about its pivotal connection with the bracket arm 20 thereby pulling the link 25 and operating the valve 27. As the rod 15 moves upwardly the ratchet teeth 28 pass the dog 29 and the latter engages the adjacent tooth when the rod is relieved of the influence of the arm 7. Thus, the rod 15 is held in elevated position and the valve 27 maintained in operated position.

30 designates the throttle valve lever of the locomotive and pivoted to the throttle valve lever adjacent to the fulcrumed end thereof is the forked or bifurcated extremity 31 of a lever 32 projecting outwardly from the throttle lever. Secured to the lever 32 adjacent to the forked end thereof is a pin 33 disposed within a slot 34 formed in one end portion of a link 35 pivotally connected with the latching dog of the throttle lever as at 36. In the initial swinging movement of the lever 32, the pin 33 engages one end wall of the slot 34 in the link 35 and moves the latter to slide the latching dog of the throttle lever out of engagement with the teeth on the quadrant and immediately succeeding this movement of the latching dog under the action of the link, the inner end wall of the bifurcated portion 31 of the lever 32 engages the adjacent edge of the throttle lever 30 so that such lever will be swung to valve closing position in the continued movement of the lever 32. In the present instance, the quadrant of the throttle lever 30 is fixed to a stud carried by the adjacent end of the boiler as shown in Fig. 3, the stud holding the quadrant stationary relatively to the lever.

37 designates a motor comprising a cylinder 38 in which is mounted for rectilinear movement a piston 39 having a piston rod 40 projecting outwardly through one end wall of the cylinder 38 and having the outer end thereof connected with the lever 32. In the present instance, this cylinder 38 is formed,

at diametrically opposite points, with trunnions 41 disposed centrally of the cylinder and journaled in alining bearings 42 carried by an appropriate support 43. Secured within an opening in the support 43 at the center of the cylinder 38 is one end of a pipe 44 and swiveled to such end of the pipe 44 is one extremity of a pipe 45, the pipe 45 having the remaining end thereof leading into the end of the cylinder 38 remote from the piston rod 40. As air or other fluid is admitted to the particular end of the cylinder through the pipes 44 and 45, the piston 39 is moved in the cylinder toward the opposite end of the latter and in this movement of the piston motion is imparted to the lever 32 through the medium of the piston rod 40 thereby unlatching the throttle valve lever and swinging the latter to valve closing position as previously described. A coiled expansion spring 46 is preferably disposed within the cylinder 38 between the piston 39 and the end of the cylinder through which the rod 40 passes and this spring is compressed by the piston in the movement of the latter under the action of the fluid so that when the fluid is released from the cylinder the spring will react to restore the piston to normal position. In the outward movement of the piston under the action of the air the cylinder 38 swings upon the trunnions 41 so that the piston rod 40 may follow the arc of the outer end of the lever 32, as is readily apparent.

In the present instance, the valve 27 is of the two-position type and comprises a casing 47 formed at diametrically opposite points with alining ports 48 with which are connected the valve ends of the brake pipe. Also formed in the casing 47 at diametrically opposite points and disposed in a plane at one side of the ports 48 and intersecting the latter are ports 49 and connected with one of the ports 49 is the remaining end of the port 44 while the other port 49 opens into the atmosphere. Rotatably mounted within the casing 47 is a plug 50 formed with a straight passage 51 and an angle passage 52. One end of the straight passage 51 is relatively wide as compared with the remaining end thereof and in one position of the plug the straight passage establishes communication between the ports 48 so that the train line air pressure may be maintained, while in the other position of the plug the relatively large end of the straight passage 51 establishes communication between one of the ports 48 and the atmospheric port 49, and the angle passage 52 establishes communication between the other port 48 and the remaining port 49. Thus, the cylinder 38 is placed in communication with the main air reservoir of the air brake system and the piston 39 actuated as previously described, while the train line air

exhausts into the atmosphere to effect an application of the brakes.

Located in the cab of the locomotive is a hand lever and connected with the hand lever through mechanism 53 is the dog 29 and by means of the hand lever and the mechanism 53 the dog may be actuated to release the rod 15 when such action is necessary or desired.

10 From the foregoing description taken in connection with the accompanying drawings, the construction, mode of operation and manner of employing my invention will be readily apparent. It will be seen that I 15 have provided a train stop whereby the propelling power of a motor car will be cut off and the air brakes applied when the car runs by a signal set at danger, and wherein the parts are so arranged and correlated as to 20 reduce the possibility of derangement to a minimum.

While I have herein shown and described the preferred form of my invention by way of illustration, I wish it to be understood 25 that I do not limit or confine myself to the precise details of construction herein described and delineated, as modification and variation may be made within the scope of the claims without departing from the spirit 30 of the invention.

I claim:

1. In automatic train stopping apparatus, the combination with a controlling element 35 of a motor car, of a motor for actuating said element to cut off the propelling power of the car, a valve controlling the operation of

said motor, a controlling device for said valve comprising a base plate, a vertical rod slidably mounted within said base plate, a bracket carried by said plate, a lever pivoted, 40 upon said bracket, a connection between one end of said lever and said valve, a connection between the remaining end of said lever and said rod, and means for sliding said rod to operate said valve to place the motor in 45 operation.

2. In automatic train stopping apparatus, the combination with a controlling element of a motor car, of a motor for actuating said element to cut off the propelling power of 50 the car, a valve controlling the operation of said motor, a controlling device for said valve comprising a base plate, a vertical rod slidably mounted within said base plate, a bracket carried by said plate, a lever pivoted 55 upon said bracket, a connection between one end of said lever and said valve, a connection between the remaining end of said lever and said rod, a bowed spring having the ends secured to the under surface of said 60 base plate, a connection between the central portion of said spring and said rod, and means for actuating said spring to elevate said rod whereby the valve will be operated 65 to place the motor in operation.

In testimony whereof I affix my signature in presence of two witnesses.

BENJAMIN R. ROACH.
